UNITED STATES PATENT OFFICE.

EDWARD McCONNELL, OF RICHMOND, VIRGINIA.

SURVEYOR'S SLATE AND BOOK HOLDER.

SPECIFICATION forming part of Letters Patent No. 733,415, dated July 14, 1903.

Application filed June 14, 1902. Serial No. 111,722. (No model.)

To all whom it may concern:

Be it known that I, EDWARD McCONNELL, of Richmond, in the county of Henrico and State of Virginia, have invented certain new and useful Improvements in Surveyors' Slate and Book Holders; and I hereby declare that the following is a full, clear, and exact description thereof, reference being had to the accompanying drawings, which form part of this specification.

This invention is a novel combined "slate-holder" and book-support particularly designed for the use of surveyors and engineers in "fieldwork" when establishing slope-stakes for railways, highways, and other engineering projects where cuts and fills have to be made; and it consists in the novel construction hereinafter described and claimed, reference being had to the accompanying drawings, in which—

Figure 1 is a perspective view of the device. Fig. 2 is a longitudinal section thereof on line 2 2, Fig. 1.

The device comprises a three-sided or U-shaped frame A, preferably formed of metal and U-shaped or channeled in cross-section, so that the "slates," plates, or sheets B, of slate, celluloid, or other suitable material, can be readily slipped laterally into or removed from the frame at will. From the vertical side of frame A extends a book-support D, which is preferably made of tubular metal for purposes of lightness and strength. This support is sufficiently long and broad to accommodate an ordinary surveyor's or engineer's record-book E (such as commonly used in recording the cross-sections and other notes in estimating cuts and fills) when opened, and the support is provided with suitable spring-clasps, such as shown at F F, to hold the book open thereon. The lower limbs of springs F F may extend back beneath the support and be attached to the side bar of frame A, as shown in Fig. 2. The frame and support both lie in the same plane, and the vertical bar of the frame is common to both.

The slates B are ruled by fine vertical lines *b* and horizontal intersecting lines *a*, like the "cross-section" or drafting paper ordinarily employed in drafting by engineers, architects, and others, the distances between the lines bearing some definite metrical proportion.

On these ruled slates are marked heavier lines C, indicating the width and side pitches or slopes for cuts and fills or embankments in railway construction. The indicating-lines C will vary in accordance with the width of cuts, (single or double track,) and I propose to provide a number of slates made of suitable material that will take the mark of a pencil, which can be "nested" one upon the other and can be carried in the same frame A. The engineer or surveyor can slip any slate on top of the others at will, and by making a selection of slates, such as will be most useful to him after plotting on one slate, he can place it at bottom and bring another unused slate into position for use.

With this device the surveyor or engineer can readily plot the ground slopes and depth of cuts or embankments upon the slates and at the same time record the memoranda thereof and calculations therefor in the book, both being conveniently at hand, thereby greatly facilitating the work and lessening labor and time ordinarily required for this work as heretofore performed.

The parts of the frame A and support D are preferably made of light non-corrosive metal, such as used in transits and other surveyors' instruments.

The said device is to be used in connection with a graduated leveling-rod and ten-foot leveling-bar to obtain the rise and fall of the ground at various angles to an established line or lines.

Having thus described my invention, what I therefore claim as new, and desire to secure by Letters Patent thereon, is—

1. The herein-described device, comprising a frame adapted to support a book, parallel pieces extending from one end of said frame and in the same plane therewith, said pieces being longitudinally grooved on their inner faces, and a series of removable superposed "slates" interposed between said pieces and engaging the grooves therein, for the purpose substantially as described.

2. In combination, a rectangular frame adapted to support a book, one end piece of said frame being elongated beyond the sides thereof, a laterally-extending piece attached to each extremity of said end piece and lying in the plane of the frame, said pieces being

longitudinally grooved on their inner faces; and a removable "slate" fitted between said pieces and confined in the grooves thereof, substantially as and for the purpose described.

3. The herein-described device, comprising a frame adapted to support a book, spring-clasps for confining the book thereon, parallel pieces extending from one side of said frame and in the same plane therewith, said pieces being longitudinally grooved on their

inner faces, and a series of removable superposed "slates" interposed between said pieces and engaging the grooves therein, for the purpose substantially as described. 15

In testimony that I claim the foregoing as my own I affix my signature in presence of two witnesses.

EDWARD McCONNELL.

In presence of—

F. C. JONES,

EDWARD TILBURY JONES.
